UNITED STATES PATENT OFFICE.

MICHAEL J. DALY, OF PITTSBURG, PENNSYLVANIA, ASSIGNOR OF ONE-HALF TO W. T. WALLACE, OF PITTSBURG, PENNSYLVANIA.

ELEVATOR-OPERATING MECHANISM.

SPECIFICATION forming part of Letters Patent No. 757,181, dated April 12, 1904.

Application filed May 16, 1903. Serial No. 157,406. (No model.)

To all whom it may concern:

Be it known that I, MICHAEL J. DALY, a citizen of the United States, residing at Pittsburgh, in the county of Allegheny and State of Pennsylvania, have invented a new and useful Improvement in Elevator-Operating Mechanism, of which improvement the following is a specification.

This invention relates to certain new and useful improvements in elevator-operating mechanism, and relates more particularly to a device whereby the operating-lever in an elevator-car cannot be actuated while the door leading to the same is open.

The object of this invention is to provide a cheap, simple, and effective device whereby when the door opening into an elevator is partially or wholly open the operating-lever in the car is locked in its inoperative position, thus preventing the starting of the car until said door has been fully closed, thus preventing accidents.

In describing the invention in detail reference is had to the accompanying drawings, forming a part of this specification, wherein like reference-numerals indicate like parts throughout the several views, in which—

Figure 1 is a sectional view of an elevator-car looking toward the door leading to the same, my device being applied thereto. Fig. 2 is a sectional plan view of the same. Fig. 3 is a detail plan view, partly in section, showing the locking device on an enlarged scale. Fig. 4 is an elevation of the same. Fig. 5 is a detail of my safety door-lock.

The reference-numeral 1 indicates the elevator-car, and 2 the operating-lever mounted therein in the usual manner, and the door 3, which is slidably mounted at the point where passage to and from the elevator is desired, has a strip or operating-cam 4 mounted thereon at a suitable elevation. One end of this strip 4 has a beveled end 5, which is adapted to engage a locking device carried by the car 1 when the door 3 is opened. This locking device carried by the car consists of an L-shaped member 6, the vertical leg of which is pivotally secured within the wall 7 of the car, and the other leg of the said member has a

notch or slot 8 formed therein, which may 50 engage a lug 9, formed on the operating-lever 2, when the same is in its central or stationary position. Mounted on the vertical leg of the member 6 is a projection 10, in which the antifriction-ball 11 is loosely held, said ball and bracket extending considerably beyond the outside edge of the car and to such a position that the ball may be engaged by the strip 4 when the door is open.

The operation of the device is as follows: 60 The elevator-car having been brought to a desired point opposite a door 3, the operator opens said door, thereby causing the beveled end 5 of the strip 4 to engage the ball 11 in the bracket 10, and thus force the member 6 of 65 the locking device to a position such as that shown by dotted lines in Fig. 3. The slot 8 in the member 6 will then be engaging the lug 9, formed on the operating-lever 2, and movement of the same will be prevented until 70 such time as the door is closed, when the strip 4 will be disengaged from the ball 11 and the member 6 will drop back, and the operating-lever may then again be operated.

I also provide a door-lock, as clearly shown 75 in Fig. 5. In this view is shown a lever 13, pivoted at 14 and provided with a cam end 12 and stop end 15. It will be plain that when the door is shut it will be held closed until the lever 2 is brought to the middle position 80 when the car is at that floor. A spring 16 is further provided to force the lever end 15 in behind the door when the same is closed. It is thus seen that the door is positively and securely closed when the elevator is not in a 85 safe position for it to be opened.

While I have described my invention in detail, it is obvious that various slight changes may be made in the same without departing from the general spirit of the invention. 90

Having fully described my invention, what I claim as new, and desire to secure by Letters Patent, is—

1. In a device of the character described, the combination with a controlling-lever, of a 95 lever fulcrumed on a door-track, a cam provided on one end of the said lever and lying in the path of the controlling-lever, and said

fulcrumed lever having an enlarged end normally lying behind the door and locking the same from opening.

2. In a device of the character described, 5 the combination with a controlling-lever having a lug on one side thereof, of an L-shaped lever, said lever being arranged in an aperture in the car-wall and pivoted at its one end therein, the vertical leg thereof normally lying 10 entirely within the wall of said car, the horizontal leg of said L-shaped lever projecting within the car and having a notch formed in its edge adapted to be engaged by said lug on said controlling-lever, a projection centrally

mounted on said vertical leg opposite said horizontal leg, the end of said projection being provided with an integral cup, an antifriction-ball loosely held in said cup, and a cam-track on the elevator-door adapted to engage said ball, as and for the purpose set forth. 20

In testimony whereof I have hereunto signed my name in the presence of two subscribing witnesses.

MICHAEL J. DALY.
